UNITED STATES PATENT OFFICE

2,683,264

COMBINED HOOK FASTENER TAPE AND
SLIDE FASTENER STRINGER

Richard J. Roseman, Newark, N. J.

Application September 27, 1951, Serial No. 248,547

2 Claims. (Cl. 2—243)

1

In the manufacture of certain garments, for example corsets and girdles, the edges of openings in the garment are provided with slide fasteners for drawing said edges together or releasing them to close and open the corresponding garment openings, respectively and hook and eye tapes are associated with the slide fasteners for preliminary securing said garment edges together preparatory to the closing operation of the slide fastener. The hook fastener tape generally comprises a multi-ply strip of fabric secured by stitching to one stringer tape of the slide fastener and having wire hooks fastened thereon by the same stitches that attach the strip to the stringer tape. Initially one end of the stringer tape extends beyond the slide fastener elements that are secured to one edge of the tape in the usual manner and the corresponding end of the hook fastener tape is usually co-extensive in length with said projecting end of the stringer tape. In applying the stringer tape to the garment, it has been customary to fold said end portion of the stringer tape into a position at right angles to the main portion of the tape so as to be coincident with the edge of the garment to which the fastener is applied, and it is desirable that the portion of the hook fastener tape on said folded portion of the stringer tape be removed both for improving the appearance of the garment and to avoid the bulk that would be incident to the folding of the stringer tape and the hook fastener tape together.

The present invention contemplates the provision of a combination fastener of the character described wherein the hook fastener tape shall be secured to the stringer tape in a novel and improved manner, so that the portion of the hook fastener on the extended portion of the stringer tape can be easily and quickly removed before the folding of the tapes and without injury to the stitching which might cause subsequent loosening of the hook fastener tape from the stringer tape; and whereby there shall be a minimum bulk or number of layers of material at the fold.

Other objects, advantages and results of the invention will be brought out by the following description in conjunction with the accompanying drawings in which:

Figure 1 is a fragmentary elevational view of the inside of a girdle having a combined slide fastener and hook and eye fastener of the type hereinbefore described, the slide fastener and hook and eye fasteners being shown in partially open position;

2

Figure 2 is an enlarged fragmentary elevational view of a portion of one stringer tape of the slide fastener and the hook fastener tape stitched thereon in accordance with the invention;

Figure 3 is a similar view showing the excess portion of the hook fastener tape removed;

Figure 4 is a rear elevational view of the stringer tape and hook fastener tape as illustrated in Figure 2;

Figure 5 is a similar view of the tapes as illustrated in Figure 3;

Figure 6 is a fragmentary elevational view of one side of the stringer tape folded preparatory to attaching it to a garment;

Figure 7 is a similar view of the other side of the stringer tape;

Figure 8 is a transverse vertical sectional view on the plane of the line 8—8 of Figure 6;

Figure 9 is a fragmentary elevational view of one side of a stringer tape folded in a different manner from that shown in Figure 6;

Figure 10 is a vertical sectional view on the plane of the line 10—10 of Figure 9; and

Figure 11 is a similar view showing the edge of the folded end portion turned away from the fastener elements and stitched to the main portion of the stringer tape.

Specifically describing the illustrated embodiments of the invention, the reference characters A and B designate respectively the two edge portions of a garment, such as a girdle, at a closure opening of the garment. Secured to the edge portions A and B are the respective slide fastener stringer tapes C that have cooperating fastener elements 1 secured along their edges and engageable and disengageable by a slider 2 for connecting and disconnecting, respectively, the edge portions A and B of the garment to close and open the garment opening. This structure so far is old and well known.

A wire fastener tape E having eye fasteners 3 thereon is secured to the inner or rear side of one edge portion of the garment to cooperate with a hook fastener tape F secured to the edge portion of the garment and having hooks 4 to cooperate with the respective eyes 3 for preliminarily drawing the garment edge portions together preparatory to the closing operation of the slider 2.

The invention is directed to a method of attaching the hook fastener tape F to the stringer tape D of the slide fastener. Initially one end portion 5 of the stringer tape projects beyond the stop 1a at one end of the row of fastener ele-

ments 1 as best shown in Figure 2. The two tapes are run through a sewing machine with the hook fastener tape F in superposed relation to the stringer tape D and the two tapes are stitched together and the hook fastener elements 4 are secured to the hook fastener tape F in a continuous operation by a line of stitches 6 that runs along the inner edge portion of the hook fastener tape and includes tying stitches 7 for securely attaching the hooks to the tape.

In accordance with the invention, at a point adjacent the stop 1a on the slide fastener stringer, the line of stitches 6 is offset as indicated at 8 and run off the hook fastener tape, being then continued parallel to but spaced from the edge of the hook fastener tape to the extremity of the stringer tape as indicated at 9. The end portion 10 of the hook fastener tape beyond the offset 8 in the stitching, is thus unstitched and free from the stringer tape D.

When it is desired to apply the assembled tapes to the garment edge portion, the free end portion 10 of the hook fastener tape is cut away as indicated at 11, and it will be noted that this cutting operation can be effected without in any way affecting the line of stitches. Accordingly there is no danger of the stitches loosening or pulling out in such a manner as to permit the hook fastener tape to become detached or loosened from the stringer tape.

Then the extending end portion 5 of the stringer tape is folded into a position at right angles to the main portion of the tape as shown in Figures 6 and 7, the extended end portion of the tape being shown in Figure 6 in its initial condition by dot and dash lines and being shown in folded position by solid lines. With this method and construction, it will be seen that there are a minimum number of layers of fabric at the fold and the hook fastener tape does not appear on the folded end portion of the stringer tape, as will be seen from Figures 1 and 7.

A modification of the invention is shown in Figures 9 to 11 inclusive. Instead of being folded on the bias as shown in Figures 1 to 8 inclusive, the extending end portion 12 of the stringer tape G is simply folded against the side of the stringer tape on which the hook fastener tape is secured. The marginal portion of the folded end portion 12 is turned away from the fastener elements 1 as indicated at 15 and said turn back portion 15 and the folded end portion 12 are secured to the main portion of the stringer tape by stitches 14.

It will be understood by those skilled in the

art that the folded end portions of the stringer tape can be secured to the main portions in any suitable manner, other than the stitches, but for the purpose of illustration the stitches 13 are also shown for securing the folded end portion 5 of the tape shown in Figures 1 to 7 inclusive.

In actual commercial manufacture of the combined slide fastener stringer tape and hook fastener tape, a plurality of series of fastener elements will be arranged along the stringer tape in a continuous operation and the hook fastener tape will be stitched to the stringer tape along the whole length of the latter, the stitches running off the edge of the hook fastener tape at the desired points with respect to the several series of fastener elements 1.

While the now preferred form of the invention has been illustrated and described, it should be understood that the steps of the method may be modified and the invention may be utilized in other types of tapes, all within the spirit and scope of the invention.

I claim:

1. An article of manufacture, comprising a slide fastener stringer tape having a series of fastener elements on one longitudinal edge thereof and a slider stop at one end of said series of fastener elements and distinctly spaced from the corresponding end of said stringer tape, a hook fastener tape superposed on said stringer tape with one end approximately coincident with said slider stop, and a line of stitches penetrating said hook fastener tape and said stringer tape adjacent one edge of said hook fastener tape, said line of stitches having a lateral portion running across said edge of the hook fastener tape short of said end of said hook fastener tape and continuing along only said stringer tape several stitches beyond said lateral portion of the line of stitches.

2. An article of manufacture as defined in claim 1 wherein the end portion of said stringer tape beyond the corresponding end of said hook fastener tape is folded upon the main portion of the stringer tape and in superposed relation to said end of the hook fastener tape, with the addition of means penetrating and securing together said folded end portion of the stringer tape and said hook fastener tape.
